BY *Has. M. Dorcas* ATTY.

UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,232, dated October 21, 1890.

Application filed May 14, 1890. Serial No. 351,807. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawings, forming a part thereof.

10 The design relates to a clay or other tile in which the ornamental effects are produced by the outline of the tile, by the surface ornamentation thereof, and by the conjunction of the two.

15 The design consists of a tile, the outline of its lower portion being formed in the main by two convex curves and two shorter convex curves, the latter uniting in a point at the end of the tile; and it also consists in a surface or-

20 namentation composed of a fleur-de-lis figure.

In the accompanying illustrations, Figure 1 illustrates the face view of a tile of the design. Fig. 2 illustrates a number of such tiles laid in quincunx order, illustrating the effect 25 of the shape or outline of the tile when associated with other like tiles.

The design relates particularly to the exposed or lower face of a tile, its upper portion

partaking of various shapes. As illustrated, the tile has diagonal upper sides *a b*, which 30 bear upper flanges. The lower or exposed portion of the tile has a substantially flat face *A*, and the shape or outline whereof tends to a cone form that is made up of two convex curves *c d* and two shorter convex curves *c' d'*, which unite and form a point *x*. The surface of the tile is ornamented by a fleur-de-lis figure *B*, of conventional form. It may be stated that in a tile so shaped, when associated with others of like shape laid in quincunx 40 order, as shown in Fig. 2, the outlines of the side of the tile extend diagonally across each other, said diagonal lines being formed of a series of convex curves made up of a curve *c* or *d* in conjunction with a short convex 45 curve *c'* or *d'*, as shown.

What I claim is—

The design for a tile and its surface ornamentation, consisting of a tile the outline of which is made up of two convex curves and 50 two smaller curves uniting in a point, and a fleur-de-lis figure on its surface, as shown.

GEO. H. BABCOCK.
